UNITED STATES PATENT OFFICE.

WILLIAM O. WORTH, OF CHICAGO, ILLINOIS, ASSIGNOR OF TWO-THIRDS TO
WILLIAM R. DONALDSON, OF LOUISVILLE, KENTUCKY, AND HENRY W.
KELLOGG, OF BATTLECREEK, MICHIGAN.

DUPLEX GAS-ENGINE.

SPECIFICATION forming part of Letters Patent No. 670,550, dated March 26, 1901.

Application filed June 13, 1899. Serial No. 720,393. (No model.)

To all whom it may concern:

Be it known that I, WILLIAM O. WORTH, of Chicago, in the county of Cook and State of Illinois, have invented certain new and useful Improvements in Duplex Gas-Engines; and I hereby declare that the following is a full, clear, and exact description thereof, reference being had to the accompanying drawings, which form part of this specification.

This invention is an improvement in duplex gas-engines in which two alternately-acting pistons are employed to propel the main shaft; and the objects of the invention are to provide novel means for compressing and storing air within the pump base or casing and to provide novel means for supplying the cylinders with explosive gases.

The invention further consists in many minor details of construction and combinations of parts, and the claims following this description summarize all that I deem novel and of importance therein.

The accompanying drawings illustrate the best form of apparatus known to me, and wherein—

Figure 1 is a side elevation of the complete engine. Fig. 2 is an end elevation thereof with one fly-wheel removed. Fig. 3 is a longitudinal vertical section. Fig. 4 is a transverse vertical section. Fig. 5 is a detail vertical section through the gas-compressing cylinder and valve. Fig. 6 is a detail view of the said gas-compression valve. Fig. 7 is a detail transverse section through the cylinders, and Fig. 8 is an enlarged detail sectional view of the fan-blade.

A designates the main shaft, which is provided with opposite cranks $a a$, which are enclosed within the hollow base W of the engine, the said shaft being journaled in removable boxes or plates $w w$, bolted over openings in the ends of base W, and on the projecting ends of the shaft are fly-wheels A', as shown, exterior to the base. The central portion of shaft A intermediate the cranks a has a central transverse slot a' in it, through which passes a reciprocating blade B, which is guided by means of plates $b b$, that extend through slot a' on opposite sides of the blade

and are connected at their extremities exterior to the outer shaft to the opposite parts b' of a split collar secured to the shaft by means of bolt b^2 . (See Fig. 4.) The objects of this split collar b' are to form a more easily-dressed guideway for blade B and to increase the diameter of shaft A intermediate the cranks a . This central portion of shaft A, with the collar and blade, is inclosed within an annular pump-chamber, the casing C of which is divided horizontally, as indicated in Fig. 4, so as to facilitate its location within the base W and its adjustment around the central portion of the shaft. The pump-casing is just as wide as blade B, which projects closely therein, said blade being of a length equal to the internal diameter of the casing; but the casing is set eccentrically to the shaft, so that the collar b' impinges against the top of the casing, as shown in Fig. 4. Obviously as the shaft rotates blade B will be rotated within the casing C. Owing to the eccentric relation of the shaft and casing, it is necessary to provide blade B with an adjustable end B', which telescopes into the main part of the blade, but is normally projected so as to bear against the wall of the casing by means of springs B^2 . (See Fig. 8.)

Air is admitted into the upper side of the pump-chamber at one side of shaft A through an inlet-port c , and the air compressed in said chamber is conducted through a port c' to a compressed-air-storing chamber or reservoir W' in the bottom of base W, as shown in the drawings. This port c' communicates with the top of the pump-chamber at the side of shaft A opposite inlet-port c . By this means at each rotation of shaft A pure air is forced into chamber W' and stored therein under pressure for use in the cylinders, as herein-after explained.

Mounted upon the base W, directly over shaft A, are cylinders D D', within which are pistons $d d'$, respectively connected by pitmen d^2 and d^3 to the cranks a , so that when one piston descends the other ascends. The construction of these pistons is no part of the present invention. The exhaust-ports E of both cylinders are located near the centers

thereof, so as to be uncovered just as the pistons reach the end of their downward stroke, and both of said ports communicate through passages E' in the walls of the cylinders with 5 a common exhaust or outlet pipe E². (See Fig. 4.) In the side wall of each cylinder, opposite exhaust-ports E and slightly below the upper ends thereof, are air-inlet ports F, which communicate through suitable pas- 10 sages in the walls of the cylinders with an air- passage F', which extends through the walls of the cylinders and base to and communi- cates with the port c' and therethrough with the air-reservoir W', so that just after the ex- 15 haust-ports of either cylinder are opened to permit the burned gases to escape the air- port is opened, admitting large quantities of fresh air into the cylinder, driving the burned gases therefrom, and filling it with fresh pure 20 air. Above ports E and near the upper ends of the cylinders are gas-inlet ports e in each cylinder, which communicate through pas- 25 sages e' respectively with cylinder D², ar- ranged about intermediate cylinders D'D' and for convenience slightly to one side thereof. Check-valves e² may be placed in passages e', so as to prevent escape of any gases from cylinders D'D' into cylinder D². For conven- 30 ience of construction the passages e' may be bored out vertically in the walls between the cylinders, and after the check-valves are dropped in place the upper ends of the pas- 35 sages can be closed by plugs e³, as indicated in the drawings. The cylinder D² is closed 40 at the bottom by a head D³, and within said cylinder is a piston-valve G, which has a central imperforate partition G', that prevents communication between the upper and lower parts of the cylinder. To said partition is at- 45 tached the end of the piston-rod H, which projects through a proper stuffing-box on head D³ and is connected to the cross-head H' below cylinder D², which cross-head is connected by a link h² to the crank-arm h' on a rock- 50 shaft h, which is journaled in suitable bear- ings in base W parallel with the main shaft and is rocked at the proper time by means of a crank-arm A⁶ on its outer end, connected to the eccentric-strap A⁵, which encircles an ec- 55 centric A⁴ on one end of the main shaft A. (See Figs. 2 and 3.) Shaft h is rocked so as to reciprocate piston-valve G once for each revolution of shaft A.

Gas is admitted into cylinder D² through 55 a central port D⁴, and in the walls of valve G on opposite sides of partition G' are ports g g', respectively adapted to register with port D⁴, Fig. 5, when the valve is in its lowermost and uppermost position, and thus admit gas into 60 the upper or lower ends of the cylinder D².

In the wall of valve G, next cylinder D and below the partition G', is a port I, which ex- 65 tends up through the wall of the valve and opens above the partition, so that said port communicates only with the interior of cyl- 70 inder D² above the valve. In the wall of the

valve G, next cylinder D', but above the par- 75 tition, is a port i, which extends through the wall of the valve and opens below the parti- tion, so that said port i communicates only with the cylinder D² below said partition. The object of this arrangement of ports is that gas will be admitted into cylinder D only on the upstroke of valve G and into cyl- 80 inder D' only on the downstroke of said valve. 75

It will be observed by reference to Fig. 5 that the gas-inlet port D⁴ registers with the inlet-ports g g' only momentarily during a fraction of the stroke of valve G', and when ports D⁴ and g register ports i' and passage 80 e', leading into cylinder D', also register. There is therefore no communication be- 85 tween the upper end of cylinder D², into which the gas is entering, and either cylinder D' or D². When the valve G rises so that ports g' and D³ register, port I also registers with passage e', leading to cylinder D; but there is no communication between the lower end of cylinder D² and either cylinder D or D'. This construction of valve and ports 90 causes the valve when moving either up or down to create a partial vacuum within that end of cylinder D² from which it is moving and to compress gas within the other end of said cylinder. For instance, if the valve be 95 moved downward before port D registers with port g a partial vacuum is created in the upper end of cylinder D², while the gas below partition G' is compressed before it is ad- 100 mitted into cylinder D². Therefore at the moment port g' registers within port D⁴ the partial vacuum in cylinder D² will be 105 sufficient to forcibly suck into cylinder D² enough gas to suffice for an explosion in cyl- 110 inder D when subsequently injected into the latter. The object of creating this partial vacuum and consequent suction is to cause the gas to enter cylinder D² very quickly, so that the engine can operate at high speed without using any extra pressure upon the gas 115 or to enable a carburetor (such as is shown in my application for Letters Patent Serial No. 719,939, filed June 9, 1899) to be em- 120 ployed in connection with this engine.

The gas compressed by the descent of the 125 valve is admitted through port i and passage e' into cylinder D' under sufficient pressure to insure its quick entrance therein. Of course upon the ascent of the valve a partial 130 vacuum is created below it, so that the gas will be sucked into the lower end of the cyl- 135 inder D² very rapidly when ports D⁴ and g' register, while the gases compressed in the upper end of the cylinder D² are simultane- 140 ously admitted into cylinder D at the proper time through passages I and e'. Cylinder D² and valve G really constitute a gas-pump, which alternately sucks in gas by means of a partial vacuum and then compresses it, and the suction takes place at one end of the 145 pump while compression is taking place at the other end.

The operation of the parts thus far described will, I think, be perfectly obvious from the foregoing description and drawings.

The cylinders D D' are sufficiently lengthy 5 to enable their upper ends to be utilized as exploding-chambers and are each provided, preferably, with a simple electrical igniting device of any suitable construction.

When the parts are in the position shown 10 in Fig. 3, the burned gases can escape from cylinder D through port E and fresh air enter the same cylinder through ports F', while a charge of air and gas has been compressed in cylinder D' and is ready to be exploded 15 therein. Upon the ignition of such gases piston d' descends and piston d rises. In so doing ports E and F in cylinder D are closed, and just as the upper end of piston d reaches the port e of cylinder D a charge of compressed gas is admitted thereinto from pump 20 D², and then during the rest of the upward stroke of piston d the charges of gas and air are compressed therein. As piston d' reaches the end of its downward stroke its ports E 25 and F are successively uncovered and the burned gases allowed to escape, while volumes of fresh compressed air are introduced therein from reservoir W'.

Having thus described my invention, what 30 I therefore claim as new, and desire to secure by Letters Patent thereon, is—

1. In a gas-engine, the combination of the cylinders, pistons and main shaft having opposite cranks, a pumping-chamber inclosing 35 a portion of said main shaft and located between said cranks, and a piston in said chamber attached to and actuated by said shaft, for the purpose and substantially as described.

2. In an engine, the combination of an air-reservoir, the main shaft, a pair of cylinders above said main shaft, and pistons in said cylinders respectively connected to the cranks of said main shaft; with a pumping-chamber 45 surrounding the main shaft between the cranks, a rotary pump-piston in said chamber connected to and actuated by the main shaft, and a port for conducting air from said chamber to said reservoir, all substantially as and for the purpose set forth.

3. In an engine, the combination of the base, an air-reservoir therein, the main shaft journaled in said base, a pair of cylinders above said main shaft, and pistons in said 55 cylinders respectively connected to the cranks of said main shaft; with a pumping-chamber in said base intermediate the cranks of the main shaft and surrounding the latter but eccentric thereto, a pump-piston in said chamber connected to and actuated by the main shaft, and a port for conducting air from said chamber to said reservoir, all substantially as and for the purpose described.

4. In a gas-engine, the combination of a 60 pair of cylinders, a gas-pumping chamber between said cylinders communicating therewith, and a single gas-inlet into said pump-

ing-chamber; with a piston-valve in said pumping-chamber having a central partition, gas-inlet ports above and below said partition 70 adapted to alternately register with the inlet-port of the pump-cylinder, and ports respectively opening above and below the partition and extending through the wall of the valve to the opposite sides of the partition, adapted 75 to respectively register with the inlet-passages of the respective working cylinders, for the purpose and substantially as described.

5. In a gas-engine, the combination of the main shaft, the pair of cylinders above the 80 same, the oppositely-working pistons therein connected to said main shaft, and an intermediate gas-pumping chamber between said cylinders, having outlets communicating therewith, and a single gas-inlet into said 85 pumping-chamber; with the piston-valve G in said pumping-chamber having a central partition, gas-inlet ports above and below said partition adapted to alternately register with the inlet-port of the pump-cylinder, and ports 90 respectively opening above and below the partition and extending through the wall of the valve to the opposite sides of the partitions, so that they are adapted to respectively register with the inlet-passages of the 95 respective working cylinders, for the purpose and substantially as described.

6. In a gas-engine, the combination of the base, the main shaft journaled on said base having oppositely-disposed cranks, the pump-chamber surrounding the main shaft intermediate the cranks, and the piston in said pump-chamber operated by said main shaft; with a pair of cylinders mounted upon said base, the pistons therein respectively connected to the cranks of the main shaft, the gas-pumping cylinder beside said main cylinders, the piston-valve therein constructed substantially as described, the rock-shaft and connections for operating said rock-shaft from the main shaft, and exhaust-ports and air-inlet ports near the lower ends of said cylinders, and the gas-inlet ports and passages for conducting gas to said cylinders from the gas-pumping cylinder, and means for igniting the 115 explosive gases, all substantially as and for the purpose set forth.

7. In a gas-engine, the combination of the base, the air-reservoir, the main shaft journaled on said base having oppositely-disposed 120 cranks, the pump-chamber surrounding the main chamber intermediate the cranks, the piston in said pump-chamber operated by said main shaft, the air-inlet port to said pumping-chamber and the outlet-port of said 125 pumping-chamber leading to the said reservoir; with a pair of cylinders mounted upon said base, their exhaust-ports, the pistons therein respectively connected to the cranks of the main shaft, the gas-pumping cylinder 130 beside said main cylinders, the piston-valve therein constructed substantially as described, the rock-shaft and connections for operating said rock-shaft from the main shaft,

the air-inlet ports and passages, whereby air is conducted into said cylinders from the said reservoir, and the ports and passages communicating with the said working cylinders 5 and the gas-pumping cylinders, and means for igniting the explosive gases, all substantially as and for the purpose set forth.

8. In a gas-engine, the combination of the cylinders, pistons and main shaft, an air-pumping chamber through which said shaft passes, and an air-storing chamber communicating with the pump-chamber, and a rotary pump-piston within said pump-chamber actuated by said shaft and playing through 15 a slot therein, for the purpose and substantially as described.

9. In a gas-engine, the combination of the cylinder, piston and main shaft, the latter being transversely slotted, an air-storing 20 chamber, and a circular air-pumping chamber through which said shaft passes eccentrically, and a pump-piston within said pumping-chamber connected to and actuated by said shaft and playing through the slot there- 25 in, and means for regulating the admission of air to the cylinder from said storing-chamber, for the purpose and substantially as described.

10. In a gas-engine, the combination of the 30 main shaft, cylinder and piston, and an air-storing chamber; with a pumping-chamber intermediate the air-chamber and cylinder through which said main shaft passes eccentrically, a rotary pump-piston within said 35 pumping-chamber attached to said main shaft, and means for admitting air from the pump-chamber to the storing-chamber and means for conducting air from the storing-chamber past the pump-chamber and to the 40 cylinder, for the purpose and substantially as described.

11. In a gas-engine, the combination of the cylinders, pistons and main shaft having opposite cranks, a circular pump-chamber inclosing 45 part of said main shaft between said cranks and located eccentrically to said shaft; and a rotary piston in said chamber attached to and actuated by said shaft, for the purpose and substantially as described.

50 12. In a gas-engine, the combination of the double-cranked main shaft, a pair of cylinders above said main shaft, pistons on said cylinders respectively connected to cranks on said main shaft, a pumping-chamber surrounding the main shaft between the cranks, and a rotary pumping-piston in said chamber connected to and actuated by the main shaft between the cranks, for the purpose and substantially as described.

60 13. In a gas-engine, the combination of a pair of cylinders, the pistons therein, the main shaft actuated thereby, the gas-pumping chamber intermediate the cylinders, the gas-inlet thereto, and the gas-ports leading there- 65 from to the cylinders respectively, the piston-valve in said chamber and the ports in said valve whereby gas is first drawn into the

pump by suction and then forced into the cylinders under compression, with an air-pumping chamber surrounding the shaft, a rotary 70 piston therein actuated by the main shaft, and means for conducting the compressed air from said air-pump to said cylinders alternately.

14. In a gas-engine, the combination of a 75 cylinder, the piston therein, the main shaft actuated thereby, the gas-pumping chamber, the ported piston-valve in said chamber and the ports controlled by said valve; with an air-pumping chamber surrounding the shaft, 80 a rotary piston therein actuated by the main shaft, and means for conducting the compressed air from said pump to said cylinder, a rock-shaft beside the main shaft and connections for operating said gas-pump piston from 85 said rock-shaft.

15. In a gas-engine, the combination of a pair of cylinders, the pistons therein, the main shaft actuated thereby, the gas-pumping chamber intermediate the cylinders, the ported piston-valve in said chamber and the ports controlled by said valve whereby gas is first 90 drawn into the pump by suction and then forced into the cylinders alternately under compression; with an air-pumping chamber 95 surrounding the shaft, a rotary piston therein actuated by the main shaft, and means for conducting the compressed air from said air-pump to said cylinders alternately, a rock-shaft beside the main shaft and connections 100 for operating said gas-pump-valve piston from said rock-shaft.

16. In a gas-engine, the combination of a 105 cylinder, the piston therein, the main shaft actuated thereby, the gas-pumping chamber, the ported piston-valve in said chamber, and the ports controlled by said valve; with an air-storing chamber, a rotary air-pumping chamber surrounding the shaft between the cranks thereon, a rotary air-pump piston playing through a slot in the shaft, means for conducting air from said air-pumping chambers 110 to the storing-chamber, and means for admitting air from the storing-chamber into the cylinders alternately. 115

17. In a gas-engine, the combination of a pair of cylinders, the pistons therein, the main shaft actuated thereby, the gas-pumping chamber intermediate the cylinders, the ported piston-valve in said chamber and the ports controlled by said valve whereby gas is drawn 120 into the pump by suction and then forced into the cylinders alternately under compression; with an air-storing chamber, a rotary air-pumping chamber surrounding the shaft 125 between the cranks thereon, a rotary air-pump piston playing through a slot in the shaft, means for conducting air from said air-pumping chamber to the storing-chamber, and means for admitting air from the storing-chamber into the cylinders alternately. 130

18. In a gas-engine, the combination of a cylinder, the piston therein, the main shaft, a gas-pumping chamber, the ports commun- 135

cating therewith, the ported piston in said gas-pumping chamber, and means for operating said ported piston from the main shaft; with a circular air-pumping chamber surrounding 5 said shaft, and a rotary piston within said air-pumping chamber connected to said shaft; an air-storing chamber connected to said air-pumping chamber, and passages for conducting air from the storing-chamber to the cylinders, all substantially as and for the purposes described.

19. In a gas-engine, the combination of a pair of cylinders, the pistons therein, the main shaft having opposite cranks, pitmen connecting 15 said cranks to the respective pistons, a gas-pumping chamber intermediate the cylinders, the ports communicating therewith, the ported piston in said gas-pumping chamber, and means for operating said ported piston from the main shaft; with a circular air-pumping chamber surrounding said shaft intermediate the cranks thereon, a piston within 20 said air-pumping chamber connected to said shaft, an air-storing chamber connected to said air-pumping chamber, and passages 25 for conducting air from the storing-chamber

to the cylinders, substantially as described and for the purpose set forth.

20. In a gas-engine, the combination of a pair of cylinders, the pistons therein, the main shaft actuated thereby, the gas-pumping chamber intermediate the cylinders, the double-ported piston-valve in said chamber and the ports respectively communicating with said cylinders controlled by said valve, whereby 30 gas is alternately drawn into the pump by suction and then forced into the proper cylinder under compression, gas being drawn into one end of the pump while being compressed and expelled from the other end thereof; with a rotary air-pump actuated by the main shaft, and means for conducting the compressed air from said pump to said cylinder.

In testimony that I claim the foregoing as 45 my own I affix my signature in presence of two witnesses.

WILLIAM O. WORTH.
